APPARATUS FOR SPRAYING MATERIAL

Charles P. Lamb and Isaac E. Schine, Bridgeport,
Conn., assignors to Cilco Terminal Company,
Inc., Bridgeport, Conn., a corporation of Con-
necticut

Application August 15, 1935, Serial No. 36,312

7 Claims. (Cl. 91—44)

The present invention relates to an apparatus for spraying material, and while the invention contemplates the spraying of any suitable material with any suitable liquid it is particularly adapted for the spraying of soft or hard coal with oil. An object of the invention is to provide an apparatus into which the coal or other material may be flowed or poured in the form of a confined compact stream, and within the apparatus will be spread into a thin layer as it flows therethrough, the oil or other liquid being sprayed thereon in a manner to substantially completely cover all particles thereof with an even film or coating, and without any waste due to evaporation, misting, or the like, the sprayed coal being then flowed from the apparatus in a confined compact stream. It is particularly proposed in the exemplary illustrated embodiment of the invention to provide a chamber into which the coal is flowed and within this chamber to provide spreading means which will cause the flowing coal to assume a thin-walled globular shape, and further to provide oil spraying means arranged both within the globular shaped flowing coal and also at its outer surface so that all particles of the coal will be reached. A further object is to dispose the oil spraying means so that they are entirely protected against contact with the flowing coal and will not therefore become clogged or impaired thereby. Another object is to provide an apparatus of simple construction, which may be readily attached in relation to a conveyor or other coal feeding means, and which may be conveniently transported when desired from one part of a plant to another. A further object is to provide an apparatus which may be easily and conveniently disassembled for cleaning or repair.

With the above and other objects in view, an embodiment of the invention is shown in the accompanying drawing and this embodiment will be hereinafter more fully described with reference thereto, and the invention will be finally pointed out in the claims.

45 In the drawing:

Fig. 1 is a vertical sectional view of the apparatus according to the exemplary illustrated embodiment of the invention, the coal conveyor being shown in side elevation, the coal being shown in heavy dot-and-dash lines, and the sprayed oil in light dot-and-dash lines.

50 Fig. 2 is a plan view of the apparatus, partially broken away.

55 Referring to the drawing the material spray-

ing apparatus, according to the exemplary illustrated embodiment of the invention, comprises a spraying chamber consisting of a lower inverted cone shaped wall 10, having a cylindrical vertically extending upper wall portion 11, and provided at its base with a cylindrical outlet wall 12. Secured to the upper marginal edge portion of the cylindrical wall portion 12 is an angular flange member 13 upon which there is removably secured the upper portion of the chamber consisting of a cone shaped wall member 14 provided at its edge with an angular flange member 15 which seats upon the flange member 13 and is secured thereto by screws 16. A cylindrical material inlet neck portion 17 is provided at the upper edge of the wall portion 14, and a diverging inverted cone shaped funnel portion 18 is mounted upon the neck portion 17.

Surrounding the cylindrical wall portion 11 there is provided an oil feeding header pipe 19, provided at equally spaced points with inwardly directed jet nozzles 20 extending through holes 21 in the wall portion 11 in order to direct the sprayed oil into the chamber, the angular relation of these jet nozzles being so arranged with respect to the angles of the conical wall portions 10 and 14 that the spray will spread to all parts of the chamber.

Within the chamber directly below the neck portion 17 there is provided a cone member 22 provided at its under side with an interiorly threaded boss 23 which is secured upon the upper threaded end of a vertically disposed pipe 24, this pipe being mounted at its lower end upon a bracket arm 25 secured to the wall portion 10. The pipe 24 is provided near its upper end within the space below the cone 22 with a series of downwardly inclined jet nozzles 26, and at its lower end is connected by suitable couplings 27 and 28 to an oil feeding pipe 29 extending through a hole 30 in the wall portion 10.

While the coal or other material to be sprayed may be fed into the chamber in any suitable manner it is preferably fed by means of a conveyor belt 31 extending over a roller 32, having its shaft 33 mounted in bearing brackets 34 secured upon a pair of beams 35 disposed above the chamber and upon which the chamber is suspended by a series of rods 36 secured at their upper ends to the beams 35 and removably secured at their lower ends to angular brackets 37, secured upon the cylindrical wall portion 11 of the chamber, by means of nuts 38 engaged upon the lower threaded ends of the rods.

The operation of the apparatus is as follows:—

The coal or other material to be sprayed is fed by the conveyor to the funnel 18 from which it passes through the neck 17 in the form of a confined compact stream. From the neck 17 it drops 5 upon the cone 22 and is spread thereby into a thin even layer which passes from the cone downwardly to the wall portion 10 and is again converged at the outlet 12 into a confined compact stream. It will be seen that the coal as it flows 10 through the chamber is in the form of a thin-walled globular body of flowing coal, so that all particles thereof are exposed either at the outer or the inner surface, both of which surfaces are of relatively large area. The oil sprayed by the 15 outer nozzles 20 covers substantially all of the outer surface of the flowing coal, while the oil sprayed by the inner nozzle 26 covers substantially all of the inner surface, and due to the flowing movement of the flowing coal particles and 20 the spreading of them over the large area globular surfaces there is a complete and even spraying of all particles of the coal by the oil. Also the oil is entirely confined within the chamber, so that there is no loss due to evaporation, misting, or 25 dripping, and all of the sprayed oil deposits on the surfaces of the coal particles. Also the arrangement of the nozzles 20 in surrounding outwardly spaced relation to the flowing coal and the nozzles 26 in the protected space below the cone 22 is such 30 that the nozzles are entirely out of contact with the flowing coal and therefore will not become clogged or impaired thereby.

In order to clean the apparatus it is only necessary to remove the screws 16, whereupon the top 35 section can be readily removed. Also the cone member 22 may be screwed off of the upper end of the support 24, so that access may be had to all of the spray nozzles.

We have illustrated and described a preferred 40 and satisfactory embodiment of the invention, but it will be obvious that changes may be made therein, within the spirit and scope thereof, as defined in the appended claims.

Having thus described our invention, what we 45 claim and desire to secure by Letters Patent is:—

1. In a material spraying apparatus, a chamber having a contracted vertically disposed material inlet opening at one end through which comminuted material is adapted to flow by gravity 50 into said chamber in a contracted substantially solid stream, and a material outlet opening at the other end in said chamber, a baffle plate in spaced and opposed relation to said inlet opening having its center axially aligned with said opening and 55 its surface inclined from said center in the direction of flow of the material and adapted to evenly spread said material as it flows through said chamber and from which the material flows in a relatively thin encompassing wall surrounding a 60 central space, and spraying means within said chamber and outwardly spaced from said encompassing wall of material adapted to direct spray upon said spread material as it flows through said chamber.

65 2. In a material spraying apparatus, a chamber having a material inlet opening at its upper end, through which material is adapted to flow into said chamber by gravity in a stream, and a material outlet opening at its lower end, spreading 70 means directly below said inlet opening from which said material flows in a circumferential wall, spraying means within said chamber outwardly of said wall of material, and spraying means below said spreading means within said 75 wall of material, adapted to respectively direct

spray to the outer and inner surfaces of said wall of material.

3. In a material spraying apparatus, a chamber having a converging material inlet opening at its upper end through which material is adapted to flow into said chamber by gravity in a stream, and a converging material outlet opening at its lower end, spreading means directly below said inlet opening from which said material flows in an encompassing wall surrounding a central space, 10 spraying means within said chamber outwardly of said wall of material, and spraying means below said spreading means within said central space adapted respectively to direct spray to the outer and inner surfaces of said wall of material. 15

4. In a material spraying apparatus, a chamber having a converging material inlet opening at its upper end, through which material is adapted to flow into said chamber by gravity in a stream, and a converging material outlet opening at its 20 lower end, a baffle plate directly below said inlet opening axially aligned therewith and having its surface inclined downwardly from the center and from which said material flows in an encompassing wall surrounding a central space, spraying 25 means within said chamber outwardly of said wall of material, and spraying means below said baffle plate within said central space, adapted to respectively direct spray to the outer and inner surfaces of said wall of material. 30

5. In a material spraying apparatus, a chamber having a converging material inlet opening at its upper end, through which material is adapted to flow into said chamber by gravity in a stream, and a converging material outlet opening at its 35 lower end, a baffle plate directly below said inlet opening having a convex upper surface from which said material flows in an encompassing wall surrounding a central space and a concave lower surface, spraying means within said chamber outwardly of said wall of material, and spraying 40 means below and within the concave lower side of said baffle plate, respectively adapted to direct spray to the outer and inner surfaces of said wall of material. 45

6. In a material spraying apparatus, a chamber having a contracted vertically disposed material inlet opening at one end through which comminuted material is adapted to flow by gravity 50 into said chamber in a contracted substantially solid stream, and a material outlet opening at the other end in said chamber, a baffle plate in spaced and opposed relation to said inlet opening having its center axially aligned with said opening and its surface inclined from said center in the direction 55 of flow of the material and adapted to evenly spread said material as it flows through said chamber and from which the material flows in a relatively thin encompassing wall surrounding a central space, and spraying means within said 60 central space disposed directly below said baffle plate having spray nozzles well within the outer edge of said baffle plate and in close proximity to the horizontal plane of said outer edge, whereby said nozzles are out of the path of said encompassing wall of material as it flows to said outlet opening, said nozzles adapted to direct spray to the inner surface of said wall of material as it flows through said chamber. 65

7. In a material spraying apparatus, a chamber having a contracted vertically disposed material inlet opening at one end through which comminuted material is adapted to flow by gravity 70 into said chamber in a contracted substantially solid stream, and a material outlet opening at the 75

other end in said chamber, a baffle plate in spaced and opposed relation to said inlet opening having its center axially aligned with said opening and its surface inclined from said center in the direction of flow of the material and adapted to evenly spread said material as it flows through said chamber and from which the material flows in a relatively thin encompassing wall surrounding a central space, the wall of said chamber between 5 a point below said baffle plate and said outlet opening having an inclined downwardly con-

verging inner surface adapted to converge said encompassing wall of material, and spraying means within said central space disposed directly below said baffle plate having spray nozzles pointed along lines at substantially right angles to said converging inner surface and positioned intermediate the ends of said surface, and adapted to direct spray to the inner surface of said converging encompassing wall of material. 5
